(57) **CLAIM**

The ornamental design for a refuge room, as shown and
described.

DESCRIPTION

The patent or application file contains at least one drawing
executed in color. Copies of this patent or patent application
publication with color drawing(s) will be provided by the
Office upon request and payment of the necessary fee.

FIG. 1 is a front side view illustrating an embodiment of our
new and ornamental design for a refuge room;

FIG. 2 is a back side view illustrating the refuge room of
FIG. 1;

FIG. 3 is a right side view illustrating the refuge room of
FIG. 1;

FIG. 4 is a left side view illustrating the refuge room of FIG.
1;

FIG. 5 is a top view illustrating the refuge room of FIG. 1;
FIG. 6 is a bottom view illustrating the refuge room of FIG.
1;

FIG. 7 is a top-right perspective view illustrating the new
and ornamental design for the refuge room of FIG. 1; and,
FIG. 8 is a top-left perspective view illustrating the new and
ornamental design for the refuge room of FIG. 1.

The broken lines and the surfaces adjacent to these edges
shown in the drawings depicts portions of the refuge room
that form no part of the claim.
